UNITED STATES PATENT OFFICE.

HENRY MAGNAN, OF BEAULIEU, MINNESOTA.

POST-PULLER.

1,295,547.

Specification of Letters Patent. Patented Feb. 25, 1919.

Application filed November 12, 1917. Serial No. 201,510.

To all whom it may concern:

Be it known that I, HENRY MAGNAN, a citizen of the United States, residing at Beau-
lieu, in the county of Mahnomen and State
of Minnesota, have invented certain new and
useful Improvements in Post-Pullers, of
which the following is a specification.

This invention relates to improvements
in post pullers and more particularly to
those of the hand-operated type. One object
is to provide a post puller of very simple
construction which is cheap to manufacture
and very efficient in operation. With the
foregoing and other objects in view the
invention consists in the combination and
arrangement of parts to be hereinafter fully
described, pointed out in the appended
claim and illustrated in the accompanying
drawing which forms a part of this specifi-
cation.

The illustration is a perspective view of
my improved post puller in operation.

The reference numeral 1 denotes a base
plate upon which the converging supports 2
are supported, said supports being
connected and braced by the block 3. A pivot 4
connects the upper ends of the said supports
2 and serves as a fulcrum for the lifting
lever which comprises the cam-shaped head
5 having the integral operating handle 6.
The said head 5 is formed with a plurality
of apertures 7 any one of which may receive
the pivot 4 so that the fulcrum point may
be changed to provide a greater or less lever-
age as desired.

To the head 5 I secure the oppositely dis-
posed lugs 8 having bent or hooked ends 8^a.
Lugs 9, oppositely disposed, are secured by
pivots 10 to the head 5 at an angle to the
lugs 8, both sets of lugs 8 and 9 extending to
the edge of the head 5, and the lugs 9 being
formed with the curved free ends 11. A

chain 12 has one of its ends permanently
in engagement with one of the lugs 8, its
other end being adapted for releasable en- 45
gagement with the hooked end 8^a of the
other lug 8, and another chain 13 has one
end permanently in engagement with one
of the curved ends 11 of one lug 9, its other
end being adapted for releasable engage- 50
ment with the curved end of the other lug
9; both of said chains being adapted for dis-
posal about the post 14 to be raised. A
contractile spring 15 secured to each lug 9 is
secured also to the lower end of the head 5 55
and serves to yieldingly draw said lugs to-
ward the lower end of said head.

In operation, with the chains 12, 13 about
the post to be raised the operator depresses
the handle 6 which causes the said chains to 60
exert a lifting strain upon the post and to
work it loose from its moorings and raise it.

What is claimed is:—

In a post puller, a supporting element, a
cam shaped head fulcrumed in said sup-
porting element and, in operation, affording
a bearing surface for the post with the mini-
mum danger of binding, hooked lugs secured
to said head in pairs, said pairs of lugs
being disposed at an angle to each other and
located above and below the point of contact
of the said head with the post, springs con-
necting one pair of lugs and said cam shaped
head, and chains carried by said hooked lugs
70
75
to engage the post.

In testimony that I claim the foregoing
as my own I have hereto affixed my signa-
ture in the presence of two subscribing wit-
nesses.

HENRY MAGNAN.
